RAIL CLAMP FOR TRAVELING BRIDGES

Bernard H. Kersting, Ben Avon, Pa., assignor to
The Dravo Contracting Company, a corpora-
tion of Pennsylvania

Application March 22, 1933, Serial No. 662,104

8 Claims. (Cl. 188—43)

This invention relates to rail clamps for carriages, and specifically for traveling bridges, and consists in improvements upon the rail clamp which is described in the specification of United States Letters Patent No. 1,764,797, granted on my application June 17, 1930. The invention is illustrated in the accompanying drawings.

Fig. I is a view in side elevation of a traveling bridge to which the invention is applied; Figs. II and III are sections on the planes indicated by the lines II—II and III—III, respectively, Fig. I; Fig. IV is a fragmentary view in side elevation, and to larger scale, showing the rail-clamp mechanism which is associated with each leg of the bridge; Fig. V is a view in plan from above of the structure of Fig. IV; Fig. VI is a view in vertical and transverse sections of the structure shown in Fig. IV, the plane of section being indicated at VI—VI, Fig. IV; Fig. VII is a view in section, taken on the plane VII—VII, Fig. IV, showing to larger scale the lower portion of a leg of the bridge; Fig. VIII is a fragmentary view, showing to larger scale a portion of the assembly as seen in Fig. IV; and Fig. IX is a wiring diagram.

Referring to Figs. I, II, and III, the numeral 2 designates a carriage in the form of a traveling bridge having legs 3 and 4, through which the bridge rests on trucks 5, and the trucks 5 move on rails 6 on the two sides of (for example) an ore pile P. This bridge is shown to be provided with a clamshell bucket 7, and with the usual operator's cab 8. Associated with each truck is a rail-clamping mechanism, in which mechanism the invention is embodied.

The clamping mechanism of each truck (cf. Figs. IV, V, and VI) includes two parts or elements, 10 and 11, each of which includes a pair of rail-engaging clamps. The two elements 10 and 11 of each truck are operated by a motor 12 borne by the truck, and the motors 12 of opposite trucks are energized from a common supply line (cf. Fig. IX). A drum 19, whose shaft 18 is borne in suitable bearing in the truck 5, is arranged with its axis of rotation transverse to the direction of bridge travel, and direct driving connection is provided between the motor 12 and the drum 19, through which, in response to motor rotation, the drum may be rotated in clockwise direction (Fig. IV) at a speed suitably related to the speed of the motor.

The two clamping elements 10 and 11 borne by each truck are essentially alike, and it will suffice to describe the element 11 in detail.

A pair of equal, symmetrically formed clamping levers 28 and 29 are pivoted upon pins 32 in a pair

of links 31, that together constitute a fulcrum block. The links extend horizontally, and the levers swing in vertical plane, perpendicular to the line of extent of a rail 6. The levers are symmetrically arranged with respect to the vertical mid-plane of the rail 6; their long power arms extend upwardly, their short work arms downwardly, and the work arms terminate in jaws 30 disposed on opposite sides of rail 6. The links 31 are supported in the structure in such manner that, while held against downward displacement, they float horizontally, in the direction of their length—in a direction, that is to say, perpendicular to the extent of rail 6. By the swinging of the levers the jaws alternately close with clamping effect upon the rail and recede from such engagement; and by the floating movement of the links 31 small irregularities in relative positions of parts find compensation, and the clamping action is always effective, with equal and opposite thrusts upon opposite sides of the rail.

For the support of the links 31, a plate 37 depends from the frame of the truck in the vertical mid-plane of the rail. This plate is recessed in its lower portion, as indicated at 14, and on opposite sides of the recess the plate carries transversely and vertically extending plates 35. Against their opposing faces the two plates 35 carry strips 36, and the horizontally extending upper edges of strips 36 afford bearing surfaces upon which the links 31, by virtue of their laterally directed flanges 33, may rest and move.

The range of floating movement of links 31 (sufficient for practical purposes) is limited, and the integrity of the assembly is assured, by forming in plates 35 and strips 36 elongate openings 34, through which the prolonged pivot-pins 32 extend.

Formed in the truck 5 is a guideway that extends vertically above the rail, and in this guideway a power block 80 is mounted to move vertically. This power block 80 is connected by equal and symmetrically extending links 81 to the power arms of the levers 28 and 29. The block 80 carries wheels 80a which co-operate with vertical guides 80b, to insure free vertical movement of the block during the operation of the clamping mechanism. It will be perceived that, as block 80 is shifted vertically up and down, the rail clamp swings in opposite opening and closing directions. The block 80 is backed by springs 52, which tend always to expand and to close the clamp and to hold the jaws 30 in engagement upon the rail 6. The opening of the jaws against the tension of spring 52 is effected by the motor

12. It will further be remarked that the force exerted by the springs 52 tends always to maintain the links 31 centered in the vertical line of power block movement: any shifting of these links transversely upon their ledges is met by an excess of spring tension exerted in opposite direction.

Upon the power arms of the levers 28 and 29 sheaves 22 and 21 are rotatably mounted. A line 20 anchored at one end to a trunnion of one of the sheaves is reeved around the sheaves, as shown in Fig. VI, and extends thence by way of suitable guide sheaves to the drum 19, upon which it is wrapped and to which at its end it is secured. As the drum 19 is by the motor 12 driven in clockwise direction (Fig. IV) the line 20 is wrapped upon drum 19, the power arms of the levers 28 and 29 are drawn together, the block 80 rises (the compression of springs 52 being increased), and the jaws 30 open.

When the jaws are thus opened, a magnetically set brake 76 (effective upon the shaft of motor 12—cf. Figs. IV, V, and IX) closes, to lock the motor and drum against rotation and to hold the clamp in its position of release. At the same time a switch 73 swings, deenergizing the motor. When any of the several conditions, presently to be described, prevails, to effect release of the brake, the springs 52 become effective, to shift the block 80 downward, to spread the power-arms of the levers 28 and 29, and to cause the jaws 30 to close with clamping effect upon the track 6. During such downward movement of the block the rope 20 is drawn away from the drum, causing the drum and motor to turn in a counterclockwise direction (Fig. IV), against the resistance, however, of a dynamic brake, to be alluded to again below.

Associated with each of the two clamping mechanisms of each truck is a limit switch 61 (cf. Fig. IX). Each limit switch is located in a housing 60 which is secured to ways in which the blocks 80 move. A finger 82 (cf. Fig. IV), borne by each of blocks 80, is so arranged that, as the block rises, it effects the shifting of the limit switch 61 associated with that particular block from the normal closed position indicated in Fig. IX to the alternate open position. In the closed position of the clamp, the finger borne by the block 80 is free of contact with the limit switch; the switch member 61 then stands in closed position. When under the driving power of motor 12 the sheaves 21 and 22 have been drawn together and the block 80 has been forced upward against spring tension, and the clamp opened, contact of the movable finger 82 (borne by block 80) with the limit switch will have effected the opening of switch member 61.

Fig. IX is a wiring diagram of the two motors 12 which are mounted one on each of the trucks 5 at the opposite ends of the bridge. Referring to this wiring diagram, the motor 12 of the clamping mechanisms 10 and 11 for the leg 3 of the bridge is adapted to be connected by means of an interlocking magnetic switch 73 with the positive and negative feed lines *a* and *b*. A foot switch 67, located in the operator's cab, is adapted to close the coil of a magnetic switch 70 in circuit with the power supply lines (P. S.) for the bridge, and the consequent energizing and closing of the switch 70 effects the connection of the feed lines *a*, *b* with the power supplying lines P. S. The motor 12 of the clamping mechanisms for the leg 4 of the bridge is (by means of a duplicate set of switches 73, 67) at the will of the operator

adapted to be connected in circuit with the feed lines *c*, *b*. It will, therefore, be understood that the motors 12 and the clamping mechanisms at each end of the bridge are subject to either joint or several operations.

When the operator desires to move the bridge along the rails 6, he closes the two foot-switches 67. This completes circuits through magnet coils 68 and causes the switches 70, normally held open, to close. The closing of the switches 70 completes a circuit through the magnet coils 72 of the interlocking switches in the two motor circuits, causing the arms 73a of switches 73 to shift to the upper of their alternate positions, whereby the circuits from the feed lines (*a* *b* *c*) are closed through the motors. Electric current is then effective to energize the motors and to turn the drums 19 (in clockwise direction, as seen in Fig. IV), thus drawing the sheaves 21 and 22 of each clamp together, raising the blocks 80, compressing the spring 52, and opening the clamps. When the clamps have been moved to fully-open position, the engagement of the movable fingers 82 on the blocks 80 with their associate limit switches 61 will effect the swinging of the switch elements to open position, whereby the circuit to the magnet coil 72 is broken and the arms 73a of the interlocking switches drop to their alternate positions, in which they close the circuits for energizing the magnet coils 77 of the 30 brake switches 75, together with the coils 86 of the circuit closers 87 (these coils being connected in parallel with coils 77). The consequent energizing of coils 77 closes switches 75, and completes the energizing circuits for the magnetic 35 brakes 76, while the simultaneous energizing of coils 86 actuates the circuit closers 87 and brings the usual controls (not shown) for the bridge-moving motors into communication with the feed lines *a* *b*. Thus, it will be perceived that when, 40 due to the action of the motor 12, the blocks 80 reach the top of their vertical travel, and effect the opening of the limit switches 61, the brake 76 is energized and locks the clamping mechanism in release. At the same time the energizing circuits for the motors are interrupted, due to the falling of switch arms 73a to their lower positions, and the controls for the bridge-moving motors are brought into circuit with the feed lines. Manifestly, so long as either clamp of 45 truck 5 is closed upon the rails—and, indeed, until both clamps of the truck are fully opened and the brake 76 applied—the bridge-moving motor cannot be energized. This feature is of notable value in practice.

When the operator removes his foot from either switch 67, the switch opens, thereby breaking either the circuit *a*—*b* or the circuit *b*—*c*. Consequently, the magnetic brake 76 is deenergized and released, and the springs 52 immediately become effective to shift the blocks 80 downward in their ways and to close the clamps upon the rails. At the same time the cables 20 and 56 are drawn in directions away from the drum, and the drum and motor shaft turn backward. The action of the springs 52 in closing the clamps tends to be very quick and violent, and the drag placed upon such action by the idling drum (19) and gearing and the shaft of motor (12) is not without further provision sufficient to obviate the objectionable violence. In solving the problem, a particularly effective use is made of motor 12. The motor 12 is so wired that when its shaft turns backward under the pull of cables 20, 56 it becomes an electric generator and great torque is required 75

to turn its rotor. This torque produces a drag that automatically increases as rotor speed increases. Another valuable feature of delay in the closing of the clamps is that time is allowed for the bridge to drift to a stop. Accordingly, a graduated braking effect is produced upon the clamps as they advance to closed position. When the clamps reach full rail-clamping position, the motor for 12 comes to rest and the braking drag created by it when in motion becomes nil.

To the end that the generator braking may be effected without injury to the motor, a resistance R (Fig. IX) is included in the motor circuit. The resistance R , indeed, is in effect two resistances r_1 and r_2 ; resistance r_1 is connected in series with the motor supply line and is effective while the motor operates for the purpose primarily intended: the opening of the rail-clamps. The resistance r_2 is arranged in shunt across the motor terminals, and when the rotor is turned backward under the pull of the cables 20, 56, the circuit through the resistance r_2 constitutes the motor a generator. The resistance r_2 then affords an electric load and affords insurance that amperage of damaging magnitude shall not flow through armature or field coils of the motor.

Still considering Fig. IX of the drawings, it will be observed that a magnetic switch 78 is interposed in circuit between feed lines (a b c) and the magnet coils of switches 73a, 75, 87. The switch 78 is held to closed position by the energizing of its coil 79 and this is effected so long as a switch 89 continues in its normally closed position. The operation of the bridge then is effected in the manner already described. When, however, the coil 79 of switch 78 is de-energized and the switch is shifted to open position, the circuits to coils 72, 77, and 86 may not be completed and the corresponding switches 73a, 75, and 87 may not be closed. Thus, when the switch 78 is open, the bridge-moving motors may not be energized, none of the clamp-opening motors 12 may be energized, and neither of the magnetic brakes 76 may be operated. In a word, regardless of the use to which the bridge may at a particular moment be applied, when the switch 78 opens, the bridge-moving motors and the clamp-releasing parts become incapable of operation. The clamps then engage the rails and continue to engage the rails until the switch 78 again is closed.

The invention includes means responsive to high wind for opening the switch 78, and thus safeguarding the bridge against injury. Advantageously, an anemometer W is perched upon the superstructure of the bridge (Fig. I). The wind wheel w (Fig. IX) of the anemometer is secured to or geared to the shaft of a small dynamo d , and the poles of the dynamo are connected in circuit with the operating coil of switch 89; the switch 89 controls the circuit for energizing the coil 79 of switch 78. The switch 89 is normally closed, but is so designed electrically that, when the wind wheel turns at or above a predetermined speed, the switch 89 opens. In consequence, the switch 78 opens, operation of the bridge ceases, and the clamps close upon the rails, or, if the clamps are at the time closed, the motors 12 may not be operated to open them, until the wind has subsided. Thus, it will be seen that the bridge may not be operated when the velocity of wind exceeds a predetermined value. The same conditions hold true when the supply voltage fails in lines P. S., or when the operator relieves pressure upon the switches 67. Hence the bridge is safe-

guarded against dangerous winds, against power failure, and against carelessness in operation.

Bridges with comparatively long spans are constructed in flexible design; that is, the construction is such that one end of the bridge may be shifted through a certain range, which is usually about equal to one tenth of the width of the span, while the opposite end remains stationary. On bridges of this description the bridge-moving drive is double, and independent motors are arranged on each truck 5, so that the legs 3 and 4 of the bridge may be shifted independently along the tracks 6.

The amount of this shifting (skewing) of the bridge is limited by means of a skew limit switch, 18 which has the function of disconnecting the current from the motor at the end of the bridge in motion, or in case where both ends are in motion—one end moving faster than the other—the advancing end of the bridge will be first slowed down 20 and then brought to rest, until the other end has advanced within the allowable skew limit. The skew limit switches are not shown in the drawings, this skewing feature of construction being well known in the art. However, it is to accommodate 25 skewing that the clamping mechanisms 10, 11 are independently operable at each end of the bridge, there being a separate switch 67 in the cab for each set of clamping mechanisms. If both ends of the bridge are to be moved simultaneously, the 30 operator simply depresses both switches 67.

In bridges of long span it is impracticable with interdependent clamps at the opposite ends of the bridge to maintain the bridge true upon its tracks; accordingly, skewing is by the independence of 35 the clamps recognized, and its effect corrected. Skewing also is advantageous when the bucket is to collect material from a wider area and, carrying it longitudinally of the bridge, deposit it again to a hopper or other receptacle. Indeed the 40 bridge can remain stationary at one end, spotted over a hopper, and the other end may range over a stock pile.

By the present invention I have provided an extremely efficient rail-clamp mechanism which, 45 due to the simplicity of its construction and light weight and to the absence of clamp weights, is relatively inexpensive to manufacture and to install. This mechanism insures the clamping of the bridge to the rails in case one of the cables 50 of the mechanism should happen to break, this being true by virtue of the fact that, whereas the cables are employed for opening the clamps, the tension of the springs 52 is effective to close them. By reason of the lazy-tongs arrangement, 55 through which the tension of the spring is made effective, the spring exerts a powerful closing force upon the clamp levers. Furthermore, by providing a pair of springs 52 for each pair of clamp jaws, exerting their tension in unison 60 upon the clamp levers, tending to spread the power arms of the clamp levers, the individual springs need not be made so heavy as a single spring would necessarily be in order to perform the same work.

It will be remarked of the springs 52 that they are assembled between the block 80 and a backing-plate 54 by means of keeper bolts 51. In the erection the springs are assembled with the block 80, the backing-plate 54, and the bolts 70 51, and these elements are introduced as an assembled unit. The bolts afford means for relieving the tension of the springs when repair is to be made. It will be noted that the lazy-tongs arrangement is such that the power is 75

transmitted with increasing effect as the jaws move toward the rail. This is highly desirable, because the spring means employed for closing the jaws inherently exerts a decreasing force 5 as the spring expands. By combining the spring, which is a source of power of decreasing value, with lazy tongs, which, as they swing, are increasingly responsive to the power, the proper clamping action is assured. The arrangement 10 of lazy tongs and spring, so that the mechanical advantage of the lazy tongs varies inversely with the power of the spring, is important also in the jaw-opening operation. Once the opening jaws are clear of the rail, it will be desirable that as 15 little work as possible be done in maintaining the jaws in open position. Considering the lazy tongs from this point of view, it will be apparent that a decreasing force is required to open the jaws, and that a relatively small force will be 20 effective in maintaining the jaws in open position. Thus it appears that the lazy tongs, combined with the spring in the manner described, is of importance and value both in the closing and in the opening of the jaws.

25 I claim as my invention:

1. In rail-clamping mechanism the combination, with a movable carriage and a rail extending adjacent the carriage and in the direction of carriage movement, of a clamping device including a pair of clamping levers fulcrumed in said carriage and adapted in the assembly to swing between rail-clamping and rail-releasing positions, means tending to hold the clamping device in rail-clamping position, means for shifting the 30 said clamping device to rail-releasing position, such means including an electric circuit, and an electric motor and a magnetic brake arranged in parallel in said circuit, a switch adapted to be engaged and swung by said rail-clamping device and adapted in its swing to break the circuit through the motor and to make the circuit through the brake, and means for breaking the 35 circuit simultaneously through both motor and brake.

40 2. A rail-clamping device for a traveling bridge including, in combination with a bridge traveling upon two spaced-apart legs, of two rails extending in the direction of crane travel, one adjacent each of the said legs, a pair of clamping levers fulcrumed pair by pair in the two legs and adapted in the assembly to swing in planes 45 transverse to the direction of bridge travel and to engage the rails, pair by pair, simultaneously upon opposite sides, means tending to hold the levers to rail-engagement, and severally operable means for rendering each of the last-named means ineffective and for swinging the levers of one pair to rail-releasing positions.

45 3. In a traveling bridge standing upon and movable upon a pair of spaced-apart legs, two rails extending in the direction of bridge movement and arranged, one adjacent each of the said legs, two pairs of clamping levers mounted, one pair in each of the said legs and adapted to 50 swing between rail-clamping and rail-releasing positions, two electrically controlled means one such means associated with each pair of levers for swinging said levers from rail-clamping to rail-releasing positions, and two switches standing 55 normally open and adapted when unrestrained to return to open position and susceptible to being closed and being maintained in closed position by the muscular effort of an attendant, the two said electrically controlled means associated with the two pairs of levers, otherwise 60

ineffective, being rendered severally effective on the closure severally of the two said switches.

65 4. A rail clamp for traveling carriages including, in combination with a rail and a carriage movable thereon, of a bearing member with upwardly facing, horizontally extending bearing surface borne by the carriage and in the assembly arranged above and extending transversely of the track, a fulcrum block resting from above upon the bearing surface of the said bearing member and movable thereon in a direction transverse to the line of extent of the rail, a pair of equal symmetrically formed clamping levers pivoted to said fulcrum block and extending in a vertical plane that is transverse to the line of extent of the said rail, adapted to swing in such plane and by simultaneous and opposite swinging, by their downward-extending work arms alternately to engage and to release said rail, a guideway in said carriage extending vertically above said rail, a power block movable in said guideway, a pair of equal links pivoted symmetrically to said power block and one to each of the clamping levers in the power arms thereof, yielding means engaging said block and tending always to shift said block downward in its guideway and tending always to maintain the said fulcrum block centered in its range of movement in the vertical line of power-block movement, and means for exerting upon the upwardly extending power arms of said clamping levers simultaneous opposite and equal clamp-opening 70 stresses.

75 5. In rail-clamping mechanism the combination, with a movable carriage and a rail extending adjacent to the carriage and in the direction of carriage movement, of rail-clamping means, means tending to hold the rail-clamping means in rail-clamping position, a clamp-releasing electric motor, an electrically operated brake for said 80 motor, means driven by said motor for swinging said rail-clamping means to release position, a source of electric energy, wiring, and a switch, the parts being so arranged that, an electric circuit being established from the source of energy 85 through said wiring and through said motor, the clamp-releasing means in their movement to clamp-releasing position engage and shift the switch, whereby the motor is deenergized and the brake is through said wiring brought into 90 circuit with the source of electric energy.

95 6. In rail-clamping mechanism the combination, with a movable carriage and a rail extending adjacent to the carriage and in the direction of carriage movement, of rail-clamping means, means tending to hold the rail-clamping means in rail-clamping position, a clamp-releasing electric motor, an electrically operated brake for said 100 motor, means driven by said motor for swinging said rail-clamping means to release position, a carriage-moving electric motor, a source of electric energy, wiring, and a switch, the parts being so arranged that, an electric circuit being established from the source of energy 105 through said wiring and through the clamp-releasing motor, the clamp-releasing means in their movement to clamp-releasing position engage and shift the switch, whereby the clamp-releasing motor is deenergized, the brake is energized and applied, and the carriage-moving motor is 110 brought into circuit with the source of electric energy.

115 7. In rail-clamping mechanism the combination, with a movable carriage and a rail extending adjacent to the carriage and in the direction

- of carriage movement, of rail-clamping means, means tending to hold the rail-clamping means in rail-clamping position, an electric motor, a normally open and magnetically applied brake 5
5 for the rotor of the said motor, and means ar- ranged between the rotor of the motor and the rail-clamping means whereby forward turning of the rotor effects opening swing of the rail-clamp- 10
10 ing means and closing swing of the rail-clamp- ing means effects backward turning of the rotor and a magnetic retardation upon the closing of the clamping means, a source of electric energy, wiring, and a switch, the parts being so arranged that, an electric circuit being established from 15
15 said source of energy through said wiring and through said motor, the consequent opening swing of the rail-clamping means throws the switch, whereby the motor is deenergized and the brake is through said wiring brought into cir- 20
20 cuit with the source of electric energy, together with a second switch arranged in said wiring and within the circuit last defined, whereby, the parts being in the positions last defined, the brake will on the swinging of the switch be deenergized and 25
25 rendered ineffective and the means tending to hold the rail-clamping means in rail-clamping position will then, subject to the electric drag of the rotor, effect the closing of the rail-clamp- 25
ing means.
- 30 8. In rail-clamping mechanism the combina- 30
tion, with a movable carriage and a rail extend-
- ing adjacent to the carriage and in the direction of carriage movement, of rail-clamping means, means tending to hold the rail-clamping means in rail-clamping position, an electric motor, a normally open and magnetically applied brake 5
5 for the rotor of the said motor, and means ar- ranged between the rotor of the motor and the rail-clamping means whereby forward turning of the rotor effects opening swing of the rail- 10
10 clamping means and closing swing of the rail- clamping means effects backward turning of the rotor and a magnetic retardation upon the clos- 15
15 ing of the clamping means, a source of electric energy, wiring, and a switch, the parts being so arranged that, an electric circuit being estab- 20
20 lished from said source of energy through said wiring and through said motor, the consequent opening swing of the rail-clamping means throws the switch, whereby the motor is deenergized and the brake is through said wiring brought 25
25 into circuit with the source of electric energy, together with a second normally open and mag- netically closed switch arranged in said wiring and within the circuit last defined, whereby, the parts being in the positions last defined, on fail- 30
ure of power the said second switch will open, the aforesaid brake will be deenergized and the rail-clamping means under magnetic retardation will close.

BERNARD H. KERSTING. 30
